UNITED STATES PATENT OFFICE

2,442,515

OPEN TOP DISPLAY REFRIGERATOR

Clifford B. Shreve, Niles, Mich., assignor to Tyler Fixture Corporation, Niles, Mich., a corporation of Michigan

Application July 2, 1945, Serial No. 602,900

2 Claims. (Cl. 312—138)

1

This invention relates to refrigerators and is more particularly concerned with refrigerators or display cases having an open top with a chamber below in which the goods to be sold are held and displayed, and from which the customer may select what is desired by free access thereto through the open top.

The present invention is directed to a novel structure superimposed above the open upper side of the refrigerator and, preferably, toward the back thereof, which, in one position, usually carrying a mirror, will add to the appearance of the refrigerator and reflect the merchandise held therein, and in another position, make the refrigerator at its rear portion and at the open upper side accessible for reserving by clerks or employees of the store. Such reserving, with my invention, is made from the back of the refrigerator and not from the front as has been previously done. The reserving or replenishment of the merchandise which the refrigerator chamber holds, as previously accomplished at the front of the refrigerator, required that a truck or other vehicle on which the merchandise was carried must traverse the aisles in which the customers are standing or walking and, when stopped at the front of the refrigerator, either discommodes or forces the customer away; while with my invention the truck or other vehicle on which the merchandise is carried to the refrigerator is back of the refrigerator, out of the way and out of sight.

The invention for the attainment of the objects and purposes stated may be understood from the following description taken in connection with the accompanying drawing, in which,

Fig. 1 is a transverse vertical section through the upper portion of an open top refrigerator equipped with my invention.

Fig. 2 is a similar fragmentary section showing the position of the reflecting mirror and the back carrying it at the time that the refrigerator is being replenished from the rear thereof, and

Fig. 3 is a fragmentary horizontal section through one end of the superimposed structure located above the main refrigerator casing.

Like reference characters refer to like parts in the different figures of the drawing.

The refrigerator structure may be of a regular and conventional form, having a vertical back 1, a vertical front 2 of less height than the back, and vertical ends 3 extending upwardly substantially to the edge of the back 1, and with a transparent plate of glass or the like at 4 between the upper edge of the front 2 and the upper end of

2

the refrigerator. Back of the front and below the open top is a chamber 5, open at the upper end or top of the refrigerator, in which the articles of merchandise, indicated in dotted lines at 6, are held and displayed and from which the customer selects and takes what is to be purchased.

Toward the rear of the refrigerator and extending above it is a superstructure comprising vertical ends 7, one extending above each of the ends

10 3 of the main body of the refrigerator, between which is a top 8 at the front extending downwardly as indicated at 9 for a short distance. The top structure is preferably made of sheet metal and has the inner or under plate thereof at its rear edge directed downwardly and rearwardly for a short distance, as indicated at 10, then bent horizontally forward as at 11 for a short distance, and terminates in an upturned lip 12 as shown (Figs. 1 and 2).

20 At the inner side of each end 7 of the superstructure an upper headed pin 13 is secured, the shank extending through the inner portion of the side 7 and the head being located back thereof, substantially directly below which is a second headed pin 14, its head being at the inner end of the shank instead of at the outer end as with the pin 13, though such specific structure is not of any essential importance. Said pins 13 and 14 are located relatively close to the rear open side 30 of the superstructure.

A back 15 having a length slightly less than the horizontal distance between the inner sides of the sides 7, at its front face is equipped preferably with a reflecting mirror 16, though so far as the present invention is concerned said mirror does not necessarily need to be used. At the rear of the back 15 brackets made from sheet metal are secured, one adjacent each end of the back, having inturned flanges 17 connected by screws to the back and triangular shaped flanges 18 extending rearwardly therefrom. The rear edges of the flanges 18 are provided with lower and upper slots 19 and 20, the slot 19 being disposed substantially at right angles to the rear edge of the flange 18, and the upper slot 20 having a horizontal forwardly extending part at the inner end of which is an upwardly extending branch as shown. At the upper edge of the back 15 and connected thereto and extending rearwardly a bar 21 is secured, provided with a downwardly turned hook at its rear end. Lighting means, indicated generally at 22, may be mounted at the rear of the depending front portion 9.

In the position of the back 15 as shown in Fig. 55 1, the rearwardly extending flanges 18 of the two

brackets are suspended from the pins 13 which are seated in the slots at 20, the shanks of the pins 14 being received in the slots 19. This holds the back in an upwardly and forwardly inclined position with the mirror located to advantageously reflect the merchandise 6 below. This is the position which the back and mirror (if used) will occupy normally.

When the merchandise is to be replenished said back and attached mirror are turned to the position shown in Fig. 2. The lower portions of the flanges 18 of the brackets described are disconnected from the pins 14 and the back 15 is swung about the horizontal axis of the pins 13 and the hook of bar 21 engaged with the lip 12, thereby holding said back member 15 in a downwardly and outwardly inclined position as in Fig. 2, the open upper end of the refrigerator being accessible both at the front and at the rear. Merchandise to replenish the stock may then be placed in the compartment 5 from the rear without discommodeing customers who may be selecting and removing merchandise at the front of the refrigerator. After the replenishment has been accomplished the back member 15 is returned to its initial position as in Fig. 1.

The construction described is of a simple character, but has proven very desirable and effective in use. While it is illustrated as applied to open top refrigerators it is of course apparent that it may also be applied to show cases of various kinds not necessarily of refrigerator construction.

The invention is to be considered comprehensive of all forms of structure coming within the scope of the claims appended hereto which define the invention.

I claim:

1. In a construction as described, a merchandise holding case having a compartment open at the top and accessible from front or rear, a superstructure extending above said case and having front and rear openings, a panel for carrying a mirror normally closing the rear opening in the superstructure and inclined forwardly and upwardly over the top opening in the case, said panel being pivoted near its top on said superstructure whereby it may be swung to an upwardly rearwardly inclined position over said top opening in the case and partially closing the front opening in the superstructure and releasable means for retaining said panel in either of said positions.

2. The elements of claim 1 in which said pivotal connection of the panel has means for providing vertical movement of the panel.

CLIFFORD B. SHREVE.
